PACKAGE FOR A TOY VEHICLE

Anson Isaacson, Great Neck, N.Y., assignor to
Aurora Plastics Corporation, West Hempstead,
N.Y., a corporation

Filed Apr. 1, 1968, Ser. No. 11,253

Term of patent 14 years

Int. Cl. D9—04

U.S. Cl. D9—193

FIGURE 1 is a perspective view of the package for a toy vehicle, taken from the front of the opened package,

FIGURE 2 is a perspective view of the opened package, taken from one side, and

FIGURE 3 is a reduced scale, perspective view of the package in its closed condition.

The bottom and sides of the package, not shown in the drawings, are planar surfaces. The dominant features of the design reside in the full line portions of the drawing, a conventional toy vehicle being shown by broken lines.

I claim:

The ornamental design for a package for a toy vehicle, substantially as shown and described.
